INVENTOR:

A. Worster

United States Patent Office.

ALVAH WORSTER, OF HANNIBAL, NEW YORK.

Letters Patent No. 91,809, dated June 22, 1869.

IMPROVED HARNESS-LOOP.

The Schedule referred to in these Letters Patent and making part of the same.

To all whom it may concern:

Be it known that I, ALVAH WORSTER, of Hannibal, in the county of Oswego, and State of New York, have invented a new and useful Improvement in Harness-Loops; and I do hereby declare that the following is a full, clear, and exact description thereof, which will enable those skilled in the art to make and use the same, reference being had to the accompanying drawings, forming part of this specification, in which—

Figure 1 is a front view of my invention;

Figure 2 is a sectional side view; and

Figure 3 shows the loop detached from the other parts.

Similar letters of reference indicate corresponding parts.

The object of this invention is to make a harness-loop that is self-adjusting, so that it will hug a thin strap or accommodate a thick one; and

The invention consists in placing the loop considerably to one side of its fastening to the strap, in such manner that the loop is held down in an elastic manner, and capable of adjusting itself to the thickness of strap in all cases, as hereinafter more fully explained.

In the accompanying drawings—

A and B are the parts of the strap;

a is the buckle; and

f, the loop.

The buckle and loop are made in two parts, and entirely separate from each other, as shown in fig. 1.

The loop f is secured to the strap A by a rivet, o, through its cross-bar e, and is supported at some distance to one side of said rivet by means of arms C C.

By attaching the loop in this manner, it is held down on the strap with a degree of elasticity, so as to adjust itself to straps of different thickness.

The arms C C are extended beyond the rivet o, in the opposite direction, as shown by gg, so as to cover the edges of the strap, between the buckle and the essential parts of the loop, and thus, by making the metallic parts more continuous, give the whole a more finished appearance.

The buckle is secured in the fold of the strap, and all the parts secured by the single rivet o, as shown.

The buckle and loop being made in separate parts, also gives a greater degree of flexibility, as a whole.

I aware that a loop somewhat similar to mine has been made in one piece with a buckle; but this I disclaim, as it forms no part of my invention.

Having thus described my invention,

What I claim as new, and desire to secure by Letters Patent, is—

As a new article of manufacture, the harness-loop g c e f, when arranged and constructed as described, and adapted to be fastened to the strap at one point only, by a single rivet, passing through the opening o, said rivet also securing the buckle, as herein shown and described.

The above specification of my invention signed by me, this 9th day of September, 1869.

ALVAH WORSTER.
